UNITED STATES PATENT OFFICE.

WILLIAM A. COVENTRY, OF LANCASTER, PENNSYLVANIA, ASSIGNOR TO GREY IRON CASTING COMPANY, OF MOUNT JOY, PENNSYLVANIA, A CORPORATION OF PENNSYLVANIA.

TOY STOVE.

Application filed June 24, 1925. Serial No. 39,203.

This invention relates to toy stoves and particularly to a toy stove which simulates a gas range.

The principal object of the invention is to provide a toy stove or range which is realistic to the extent of simulating a fire.

Another object of the invention is to provide a safe, self-contained toy stove which simulates a multiple burner gas range.

A further object of the invention is to provide a simple, inexpensive toy stove construction.

Other objects of the invention will be apparent from the following disclosure.

In the form of the invention illustrated in the drawings, the stove comprises a cast iron top and a cast iron bottom, each of which are separated from the side walls of the stove. The entire stove is held together by means of bolts which pass vertically through the stove and serve to clamp the side walls between the top and bottom. One section of the top of the stove is in the form of the utensil supporting grating of a gas range; and miniature electric lamps are mounted in positions corresponding to the burners of the range. These lamps are selectively controlled by switching means actuated by handles in the form of the valve handles of a gas range. Between the utensil supporting grating and the lamps, there is placed a piece of transparent red celluloid which effects simulation of a fire when the lamps are burning. The lamps are energized by a suitable battery which may be separate from the stove, but is preferably concealed within the stove so as to make a unitary organization which is complete in itself.

Fig. 1 of the drawings is a front elevational view of a stove embodying the present invention.

Fig. 2 is a cross sectional view taken on the line 2-2 of Fig. 1.

Fig. 3 is a top plan view of the stove shown in Fig. 1.

Fig. 4 is a detailed sectional view taken

on the line 4-4 of Fig. 3, and showing a suitable arrangement for mounting the 50 miniature electric lamps.

Fig. 5 is a schematic diagram showing the arrangement of the electric wiring.

Referring particularly to Figs. 1 to 3 inclusive, the stove disclosed comprises a 55 cast iron bottom 1, having integral therewith a band of metal 2 which embraces the bottom and projects both above and below it. The top of the stove 4 is preferably made of cast iron and has integral therewith a band of metal 5 which depends from its edge in the form of a skirt. The stove has a front member 6 which may be made of cast iron and which rests upon the bottom 1 and is held against the metal band 2 60 by protuberances 7. These protuberances are integral with the bottom 1 and project upward from it in such positions as to leave a small amount of space between the protuberances and the band of metal 2. The 70 stove is provided with a back and sides which may be conveniently formed from a single piece of sheet metal 8, bent into U-shaped form and placed with one edge 75 against the bottom 1 in the same manner as the front 6. Protuberances 9, similar to protuberances 7, serve to hold this U-shaped piece of sheet metal against the metal band 1. The top 4 of the stove rests upon the upper edge of the top, back and sides and is provided with protuberances (not shown) such as 7 and 9 which hold the parts against the upper edge of the skirt 5. Suitable bolts 12 and 13 pass vertically through the stove, and thus clamp the front, back, and 80 sides between the top and bottom. 85

As shown in Fig. 3, the stove is disclosed in the form of a combination coal and gas range, the left hand section corresponding to a coal range and the right hand section corresponding to a gas range. The gas portion is in the form of a four burner gas range, and comprises utensil supporting gratings designated in general by numeral 20, and handles 21, 22, 23 and 24 in the 90 form of the valve handles of a gas range. 95

Mounted in position corresponding to the burners of the range are miniature electric lamps 21^a, 22^a, 23^a, and 24^a, corresponding respectively to the similarly numbered valve handles. As illustrated in Fig. 3, in connection with valve handle 22, each of the valve handles is arranged to actuate suitable switching mechanism as for example a knife blade switch. This switch may consist of a knife blade 30 moved by handle 22 into and out of engagement with switch jaws 31 mounted in any suitable manner on panel 35 (Figs. 3 and 4).

The wiring connections are clearly disclosed in Fig. 5 which shows a source of current such as a battery 32 connected to energize all of the lamps. This battery is preferably located within the stove, as shown in Fig. 1, and may have one terminal connected to the metal work of the stove as indicated by the symbol for ground in Fig. 5. The other terminal of the battery is connected to each of the lamps and the switches 21^b, 22^b, 23^b, and 24^b, corresponding to the respective valve handles, are connected to selectively complete the circuits from the lamps to the metal work of the stove.

As shown in Fig. 4, the miniature lamps may be mounted in suitable sockets associated with a panel of insulating material 35 which is spaced from the top of the stove 4 by spacers 36 and is bolted to the top by suitable bolts 37. The sockets may be molded into the panel or fastened thereto in any suitable manner. Between the lamps and the utensil supporting grating is a sheet of colored material 38 such as red celluloid, or the like, which effects simulation of a fire when the lamps are burning.

The front of the stove may be provided with dummy doors 40 and 41, and with an operative oven door 42 which renders the battery 32 accessible. As shown in Fig. 1, part of the gas range projects beyond the stove proper and the insulating panel 35 may be provided with a groove 50 (Fig. 4) which receives the upper edge of that part of the sheet metal 8 which forms the right hand side of the stove.

It is seen that the construction disclosed is an exceedingly simple and readily manufactured one, and that therefore the cost of producing the stove is minimized. While the stove has been described as having certain parts of cast iron and others of sheet metal, it is obvious that any of the parts may be made either of cast iron or pressed sheet metal, as desired. The stove is realistic to the extent of simulating a fire and yet it is absolutely safe for children of any age.

It is realized that the invention may be embodied in forms other than the one particularly disclosed, and hence it is desired that the disclosure be considered as illustrative and not as limiting.

Having thus described my invention, what I claim is:

1. A toy stove comprising a utensil supporting grating in the form of the grating of a gas range; a miniature electric lamp beneath said grating; a battery within said stove; a switch adapted to operatively connect said lamp with said battery; means to actuate said switch, said means being in the form of the valve handle of a gas range; and a red transparent colored medium between the lamp and the grating to effect simulation of a fire when the lamp is burning.

2. A toy stove comprising a utensil supporting grating in the form of the grating of a multiple burner gas range, miniature electric lamps mounted in positions corresponding to the burners of a gas range; a battery concealed within said stove, means to selectively connect said lamps to said battery, and a transparent colored medium beneath said grating to effect simulation of a fire when the lamps are burning.

3. A toy stove comprising a utensil supporting grating in the form of the grating of a gas range, a miniature electric lamp beneath said grating, and a transparent colored medium between said grating and said lamp to effect simulation of a lighted gas burner when the lamp is burning.

4. A toy stove comprising a utensil supporting grating in the form of the grating of a gas range, and means comprising an electric lamp situated beneath said grating to simulate a lighted gas burner.

5. A toy stove comprising a utensil supporting grating in the form of the grating of a gas range, a miniature electric lamp beneath said grating, a battery concealed within said stove, switching means adapted to operatively connect said lamp with said battery, and a sheet of colored transparent material between said lamp and said grating to effect simulation of a fire when the lamp is burning.

6. A toy stove comprising a utensil supporting grating in the form of the grating of a gas range, a miniature electric lamp beneath said grating, switching means adapted to control the operation of said lamp, and a transparent colored medium between the lamp and the grating to effect simulation of a lighted gas burner when the lamp is burning.

7. A toy stove comprising a utensil supporting grating in the form of the grating of a multiple burner gas range; miniature electric lamps mounted in positions corresponding to the burners of a gas range; a battery concealed within said stove; a plurality of switches adapted to selectively connect said lamps with said battery; means on the front of the stove to actuate said switches, said means comprising a plurality

of handles in the form of the valve handles of a gas range; and a sheet of red transparent material beneath said grating to effect simulation of a fire when the lamps are 5 burning.

8. A toy stove comprising a utensil supporting grating in the form of the grating of a multiple burner gas range; miniature electric lamps mounted in positions cor-

responding to the burners of a gas range; 10 a battery; a plurality of switches adapted to selectively connect said lamps with said battery; and means on the front of said stove to actuate said switches, said means comprising a plurality of handles in the 15 form of the valve handles of a gas range.

WILLIAM A. COVENTRY.
